UNITED STATES PATENT OFFICE.

DAVID E. BANGS, OF MEDFORD, MASSACHUSETTS.

VALVE FOR VAPOR-BURNERS.

SPECIFICATION forming part of Letters Patent No. 312,067, dated February 10, 1885.

Application filed December 18, 1883. (No model.)

To all whom it may concern:

Be it known that I, DAVID E. BANGS, of 5
Medford, in the county of Middlesex and State
of Massachusetts, have invented certain new
and useful Improvements in Valves for Va-
por-Burners, of which the following is a full,
clear, and exact description.

This invention relates to improvements in
that class of vapor-burners wherein steam is
10 combined with the gas and in such condition
consumed at the burner.

The object of the invention is to provide
novel means for delivering combined steam
and gas to the burner, and automatically con-
15 trolling the quantity of water delivered to the
chamber wherein the steam is generated by
the heat of the flame from the burner. This
I accomplish in the manner and by the means
hereinafter described and claimed, reference
20 being had to the accompanying drawings, illus-
trating my invention, in which—

In Sheet 1, Figure 1 is a view in perspec-
tive of a vapor-burner for the burning of the
vapor of hydrocarbon oil and steam, having
25 the present invention combined therewith.
Fig. 2 is a vertical longitudinal section of the
present invention, with a detail side and de-
tail sectional view of the vapor-burner; Fig.
3, a vertical cross section on line 3 3, Fig. 2.
30 In Sheet 2, Fig. 4 is a view in perspective
similar to Fig. 1, but with some of the parts
removed. Fig. 5 is a vertical cross-section on
line 5 5, Fig. 1.

In the drawings, A represents the burner-
35 tube of a vapor burner, having jet-holes *a*, at
which the vapors of the hydrocarbon oil and
steam are burned, the oil being supplied from
a pipe, B, connected to and leading from a
40 tank or reservoir holding the oil, through
pipes C and D to the burner.

E is the chamber or boiler for the water, and
in which the steam is generated, the steam
passing through a pipe, F, into a pipe or
chamber, G, where it becomes superheated,
45 and then passes through a pipe, H, into the
pipe B, to there combine with the oil as it en-
ters therein, and with it pass to the burner-
tube A to be burned, all substantially as de-
scribed and shown in a patent granted to me
50 on the 29th day of January, 1884, No. 292,616,
and needing no particular description herein.

H' is a tank or reservoir, into which water

enters through a pipe, J, and its downwardly-
projecting nozzle K, from any suitable and con-
stant supply. The nozzle or inlet K is pref-
55 erably of small diameter, for the water to pass
through it into the tank slowly and in a small
quantity at a time. A pipe, L, connects the
tank H' at or near its bottom with the boiler-
chamber E, at or near its bottom, running in an 60
inclined direction, as shown, to insure a free
flow of the water by its gravity.

M is an air-tight cylinder or float, located
in the tank H', so that as the water flows through
the nozzle K into and fills the tank H' and the 65
water-chamber E the float M, from its buoy-
ancy, will rise in the tank accordingly, and
when the water is at the desired height in the
boiler for the generation of the required amount
of steam the float M will then abut by its up-
70 per surface, N, against the open end *b* of the
nozzle K, and, acting as a valve, will close said
opening and stop the water from entering the
tank so long as the water is at such height;
but as the water in the boiler-chamber becomes 75
vaporized, and consequently diminishes in
quantity, the quantity in the tank will corre-
spondingly diminish, and the float will then
fall from its seat on the end *b* of the nozzle K,
allowing water to again enter the tank until 80
the water in the boiler is again at the right
height, when the float will again close the in-
let *b* and stop the flow of the water, and so on
during the operation of the burner. The float
85 M in its upward and downward movement in
the tank is guided by eyes *d*, secured on op-
posite sides of the tank, arranged to slide over
vertical guide-rods *f*, attached to the bottom
of the tank. An elastic washer, *g*—such as in-
dia-rubber or other suitable elastic material—is 90
secured to the float M, where it abuts against the
inlet-pipe, to secure a close fit at such point and
insure the closing of the inlet to the entrance
of water into the tank. The movements of the
float when the burner is in operation are very 95
slight, as a slight variation of the amount of
the water in the steam-generating chamber
instantly causes the float to rise or fall accord-
ingly, and thus close or open the water-sup-
ply pipe to the tank.

In the operation of vapor-burners in which
steam is combined and burned with oil-vapors,
it is very important that there should be a con-
stant, uniform, and the right amount of steam

for the proper combination with the oil and the best practical results in the operation of the burner, for if less steam is generated, more or less smoke and carbon are produced, lessening the amount of heat and the efficiency of the burner; and if too much steam is generated the flame will be diminished and probably go out, and it is also important that such should be accomplished automatically, and not left for the care and attention of the attendant. In the present invention the amount of steam necessary for the best practical results in burning a vapor-burner is secured, as the float or valve M automatically regulates and controls the amount of water entering the boiler-chamber for the generation of the requisite amount of steam.

In lieu of an air-chamber for the float, a piece of cork or any material that is of less specific gravity than the water can be used, and in lieu of having the float abut against the nozzle itself it can operate through a system of levers, and in such case the water could enter at the bottom of the tank, but as described and shown is simple, efficient, and practical. The boiler-chamber for the best practical results and to allow sufficient space for the generation of steam should be kept about one-half full. The float can be guided in its movements in other ways than as shown.

Having thus described my invention, what I claim is—

1. The combination, in a vapor-burner, of a burner, an oil-pipe, and a steam-chamber delivering combined steam and gas to the burner, said steam-chamber being adjacent to and heated by the flame from the burner, and provided with a water-supply and an automatically-operated float or valve controlling the supply of water to the steam-chamber, for the generation of the proper quantity of steam to be combined with the vaporized gas, substantially as described.

2. The combination, in a vapor-burner, of a burner, A, an oil-pipe connecting therewith, a water-chamber adjacent to and heated by the flame from the burner to generate steam, and connected with the oil-pipe to deliver steam thereto, a water-supply delivering water to the said chamber, and a float or valve

operated by the supply-water to control the supply of water and the generation of the proper quantity of steam delivered to the oil-pipe, substantially as described.

3. The combination, in a vapor-burner, of a burner, A, an oil-supply pipe, H, connecting therewith, a water-chamber adjacent to and heated by the flame from the burner and connecting with the oil-pipe to deliver steam thereto, a water tank or reservoir connected with the said chamber, a water-pipe for delivering water to the tank or reservoir, and a float or valve operated by the water delivered to the tank or reservoir to control the inlet of water through the water-pipe, substantially as described.

4. The combination of a burner, A, an oil-supply pipe, H, connecting therewith, a steam-superheater connected with the supply-pipe, a water-chamber communicating with the superheater, and arranged adjacent to and heated by the flame from the burner to generate steam, a water-supply connected with the water-chamber, and an automatically-operated float or valve controlling the delivery of water to said water-chamber for the generation of the proper quantity of steam to be delivered to the oil-pipe, substantially as described.

5. The combination of a burner, A, an oil-supply pipe, H, connecting therewith, a steam-superheating chamber, G, connected with the oil-supply pipe, a water-chamber, E, communicating with the superheating-chamber and arranged adjacent to and heated by the flame from the burner for the generation of steam, a water tank or reservoir connected with the water-chamber, a water-supply pipe having an orifice for delivering the water-supply to the tank or reservoir, and a float or valve operated by the water in the tank or reservoir to control the delivery of the supply of water thereto, substantially as described.

In testimony whereof I have hereunto set my hand in the presence of two subscribing witnesses.

DAVID E. BANGS.
